UNITED STATES PATENT OFFICE.

TURNEY E. BUCK, OF SPRINGFIELD, ILLINOIS.

DRAFT-CONTROLLER.

1,252,773.

Specification of Letters Patent. Patented Jan. 8, 1918.

Application filed December 15, 1915. Serial No. 67,052.

To all whom it may concern:

Be it known that I, TURNEY E. BUCK, a citizen of the United States, residing at Springfield, in the county of Sangamon and State of Illinois, have invented a new and useful Draft-Controller, of which the following is a specification.

The invention is applicable to steam locomotives and relates to a system of fluid-operated valves and connections adapted to control the draft in the smoke-box of the locomotive.

The purposes of the invention are: to provide in conjunction with a working-pressure valve adapted to remain closed under the normal predetermined working pressure and adapted to open automatically under steam pressure somewhat greater than the normal working pressure and less than the extreme pressure which is necessary to operate the safety valve; automatically operating means for checking the draft in the fire box during the time that the steam pressure in the boiler is greater than the normal working pressure and less than the extreme safe pressure, thereby preventing frequent and unnecessary blowing off through the safety valve.

The invention is illustrated in the annexed drawing and will be hereinafter described and the novel features thereof will be recited in the claim.

Figure 1 is a diagram showing the apparatus in place on a locomotive.

Fig. 2 is an enlarged diagrammatic view, partly in section, showing the details of the several valves and appurtenances, and Fig. 3 is a diagram showing the position of the air-intake in the smoke box.

The same reference numerals designate like parts in the different views.

The boiler 1, the smoke box 2 and the compressed-air reservoir 3 may be of any usual or approved construction.

The working-pressure valve 4 and the safety valve 5 are in communication with the steam space of the boiler. The valve 4 is adapted to open when the predetermined working pressure is exceeded. The valve 5 may be of any approved construction adapted to open when the maximum safe steam pressure is exceeded. The valve 17 is in communication with the air reservoir 3 through the pipe 8. The construction and co-operation of valves 4 and 17 will be described later. A second pneumatic valve 18 is in communication with the safety valve 5

and is adapted to be operated in one direction by steam escaping through the valve 5 when the maximum safe steam pressure is reached, and to be operated in the reverse direction by compressed air from the reservoir 3 supplied through the pipe 9. Time recording mechanism of any approved construction is housed in a casing 12 located in any convenient position in the cab of the locomotive. An air cylinder 67 adjacent to the casing 12 is equipped with pneumatically operated means adapted to co-operate with the time recording mechanism housed in the casing, to make a complete record of the time that the safety valve is blowing off into the cylinder 18. Within the cylinder 18 is a piston (not shown) adapted to be operated by steam flowing from the safety valve 5 into the cylinder while the safety valve is blowing off to open communication between the pipes 9 and 10. The pipe 10 conveys compressed air from the cylinder 18 into the cylinder 67 to cause the recording mechanism in the casing 12 to operate during the whole time that the safety valve is blowing off into the cylinder 18.

The chamber 44 of the check draft valve 6 is in communication with the interior of the smoke box 2. A pipe 7 conveys compressed air from the interior of the valve 4 to the piston chamber of the valve 6.

Within the valve 4 is a flexible disk 31 provided with a central stud 32 adapted to normally close the steam inlet port 33 inter-communicating between the chambers 21 and 22. A leak-port 41 in the wall of the steam port 33 extends outwardly through the valve body and steam in the steam port 33 when the valve is closed leaks through the port to the atmosphere.

A piston 38 is adapted to slide in the chamber 21. A spring 39 adapted to withstand normal working pressure of steam in the valve, acts on the piston 38 and through it on the disk 31 to cause the stud 32 to close the port 33. In case of excessive pressure the spring 39 will yield and permit the springy disk 31 to act to retract the stud 32, to permit steam from the chamber 21 to pass into the forward part of the chamber 22 to act on the piston 34.

A double piston 34 is adapted to slide in the chamber 22. The pipe 7 is in communication with that part of the chamber 22 which is between the heads of the piston 34, and an exhaust port 40 is in communication with the same part of the chamber, so that

when the piston 34 is in the position shown, air from the pipe 7 will be discharged through the port 40.

A way 35 in communication with the air reservoir through the pipe 8, and in position to communicate with the central part of the chamber 22, has a branch 36 in communication with that part of the chamber 22 which is beyond the right hand head of the piston 34.

When the pressure in the boiler is greater than the normal working pressure and less than the maximum safe pressure, the steam from the boiler, entering the valve through the pipe 37, will act on the disk 31 to cause it to retract the stud to uncover the port 33, and thereupon the steam passing through the port 33 will act on the left-hand end of the piston to slide the piston to the right to cause the left-hand piston head to cover the port 40 and to cause the right-hand piston head to uncover the way 35. The air trapped in that part of the chamber 22 beyond the right-hand piston head will be initially at reservoir pressure, but will be re-compressed by the moving piston and when the steam pressure on the left hand end of the piston ceases the re-compressed air will act to slide the piston to the left to its initial position. When the piston 34 is at the right hand limit of its travel compressed air from the reservoir 3 will flow through the pipe 8 and the way 35 to the part of the chamber 22 which is between the heads of the piston 34 and thence through the pipe 7 to the interior of the valve 6.

The valve 6 has a flared base 42 rigidly connected with the smoke box 2, and provided with openings 43 for admitting air to the chamber 44; it also has a cylindrical chamber 45, and a port 46 in communication with the pipe 7. A partition 47 separates the chambers 44 and 45. A valve stem 48 is adapted to slide in a central hole 49 in the partition 47. A piston 50 rigid on the stem 48 is adapted to slide in the chamber 45. A tapered plug 51, rigid on the stem 48 is fitted to a tapered seat 52 in the base 42. A spring 53 surrounds the stem 48 between the piston 50 and the partition 47. Inward sliding of the piston to open the valve will cause compression of the spring, and the spring will act to push the piston outward to close the valve. A bent pipe 54, (Fig. 3) connected with the base 42 extends into the smoke box and the lower terminal of the pipe preferably rests on the plate 55, adjacent to the exhaust nozzle 56 and below the petticoat pipe 57, so that the outlet of the pipe 54 is in the zone of the exhaust. The purpose of this arrangement is to heat the air during its delivery into the smoke box and thereby avoid sudden changes of

temperature in the box. If cold air were admitted directly to the smoke box it might cause sudden contraction of the metal and result in loosening the flues, or other injury to the boiler.

I am aware that check draft valves in conjunction with the smoke boxes of locomotives have been used to check the draft and thereby diminish the generating of steam so as to prevent too frequent and unnecessary blowing off of the safety valve; I therefore do not claim broadly a draft-controlling valve in co-operation with a safety-valve; but I am not aware of the prior use of a pneumatically operated check valve co-operative with a working-pressure valve adapted to render the check valve effective when the steam-pressure in the boiler is above the predetermined working pressure but below the maximum safe pressure.

Having fully described my invention, what I claim as new and desire to secure by Letters Patent is:

In a draft controller, the combination of a working pressure valve having a cylinder and a two-headed piston slideable in the cylinder; an air reservoir; means for supplying compressed air at reservoir pressure alternately to the sides of one head of the piston as the piston reciprocates; automatic means adapted to admit steam at abnormal pressure against one end of the piston to slide the piston in one direction to re-compress air at the other end of the piston, and adapted to shut off the steam upon the cessation of the abnormal steam pressure and thereby permit reverse sliding of the piston by the re-compressed air; a draft-check valve having a cylinder and a piston slideable in the cylinder; and means for conveying compressed air from the cylinder of the working pressure valve into the draft-check valve cylinder to maintain reservoir pressure on the draft-check valve piston; all co-acting to keep the draft-check valve constantly open during abnormal steam pressure against the piston of the working pressure valve, and upon cessation of the abnormal steam pressure to permit the re-compressed air in the working pressure cylinder to slide the piston in said cylinder to close communication with the air reservoir and to permit the air in the draft-check valve cylinder to exhaust through the working pressure valve to the atmosphere.

In witness whereof I have hereunto signed my name at Springfield, Illinois, this 16th day of September, 1915.

TURNEY E. BUCK.
